SYSTEM OF STROBOSCOPIC
RADIOGONIOMETRY

René Jean Hardy, Paris, France

Application November 30, 1931, Serial No. 578,192
In France December 4, 1930

10 Claims. (Cl. 250—11)

This invention relates to radio-direction finding apparatus of the kind in which a stroboscopic device rotates synchronously with a group of two receiving frame aerials arranged at right angles 5 to each other and is illuminated by the amplified current from the aerials.

The object of the invention is to provide apparatus of this kind which will permit the determination of the direction of a source of radio-electric emission with greater precision than the known devices and without any possible uncertainty.

According to the invention there is provided radio-direction-finding apparatus of the kind referred to above wherein the two receiving frame aerials are suitably tuned and connected respectively to impedances which comprise identical windings wound reversely and arranged to influence a tuned common impedance connected 20 through one or more reinforcing or amplifying stages to impedances or a group of impedances, combined if desired with amplifying devices, controlling the illumination of the luminous sources of the stroboscopic device.

25 In order that the invention may be clearly understood and readily carried into effect the same will now be described with reference to the accompanying drawings in which:—

Fig. 1 is a diagrammatic general view showing 30 the method of action of rotating orthogonal frame aerials on the luminous sources for lighting or extinguishing the luminous sources to give a stroboscopic effect.

Fig. 2 is a diagrammatic elevation showing the 35 arrangement of index and dial of the stroboscopic device on the rotating frames.

Fig. 3 is a detail of the rotating index.

Fig. 4 shows diagrammatically how any uncertainty which arises at 180° is removed.

40 Fig. 5 is a diagrammatic detail of a device different from Fig. 1.

Fig. 6 is a general view showing diagrammatically the rotary frames, and amplifying and indicating devices.

45 Fig. 7 shows the curves of intensity of reception of the frames, according to their orientation.

Fig. 8 is a series of explanatory curves.

Fig. 9 is a diagram showing the angular deflections of the lamp illuminations indicating the direction of the emitting station.

As shown in Fig. 1, there are used two orthogonal frame aerials 1, 2, tuned by means of variable condensers 3, preferably coupled mechanically. The tuning circuits 4, 5 of the condensers 55 are in the circuit respectively of the identical self

inductances 6, 7, which are wound in contrary directions.

The self inductances 6, 7, are arranged close to a self inductance 8 tuned to the same wave length, and connected to the grid 9 of an amplifying valve 10 for example, the plate 11 of which comprises in its circuit a self inductance 12 tuned to the same wave length as 8. The self inductance 12 is arranged so as to influence the two self inductances 13, 14.

The impedance 13 is in series with a uni-directional resistor 15, and a resistance 16 forming part of the grid circuit of the valve 17, 15 being an element intended to rectify high frequency current transmitted by impedance 13. For this purpose for example may be used a galena crystal. An impedance 18 is interposed between the plate of the valve 17 and an illuminating device such for example as a neon tube 19. A circuit composed of a resistance 20 and a capacity resistance 21 is in shunt with the neon tube 19.

Due to this device, when there is an equilibrium of current in the frames 1 and 2, the currents passing through the impedances 6 and 7 are equal and of contrary direction, so that their effect on the impedance 8 counter-balances each other.

When the currents are unequal the action of one or the other impedance 6 and 7 on 8 predominates and produces in said impedance 8 a current which is amplified by valve 10. Therefore, as soon as there is a difference between the currents in the frames 1 and 2 and consequently in the high frequency in inductances 8—12 and 13, a rectified alternating current will be produced, and consequently a uni-directional alternation will act on the grid of the valve 17. The direction of the current which flows is determined by the element 15, and there will be a displacement of the mean tension of the grid of 17 as soon as a high frequency alternating current is impressed on inductance 13.

The direction of connection of the device 15, galena crystal or otherwise, will be so chosen that the potential of the grid is displaced negatively, when an alternating current, no matter how feeble, is impressed on inductance 13.

The plate current of 17, which depends on the positive or negative value of the grid thereof, is reduced to the minimum value necessary to light up the neon tube 19.

The impedance 18 prevents any high frequency current passing into the neon tube.

As soon as the equilibrium of the currents in the frames 1 and 2 is destroyed or as soon as there is a high frequency current of different 55

value in 1 and 2, the tension of the grid of the valve 17 becomes more negative, and the plate current, which was just sufficient for illuminating the neon tube 19, is reduced by the lowering 5 of the mean potential of the grid, and the neon tube 19 is extinguished with the least current. This sensitivity of extinction or illumination depends on the characteristics of the luminous source, which may naturally be a device different 10 from a glow discharge tube. There may be used in fact an arc or a filament lamp or a suitable relay, mechanical, electrical or otherwise, controlling the illumination of the extinction of the luminous source in view. The sensitivity 15 may be made as great as desired, for example by a suitable increase of the number of amplifying stages, determining the illumination of the neon tube 19 by the absence of the alternating current in 8, and the extinction of this tube when there is an alternating current in 8.

The impedance 14 which, like the impedance 13, is coupled to 12, is connected to the grid of the valve 22, the plate of which also comprises a choke 23, connected to an illuminating device 25 such as neon tube 24 similar to the tube 19 across which, like the tube 19, is connected a capacity and resistance 25. The grid potential of the valve 22 is such that said valve operates as a detector and the plate potential is such that the illumination of the tube 24 is produced when there is a high frequency current in 8.

It will therefore be seen that the neon tube 19 will light up in the absence of alternating current in 8, and will be extinguished when there 35 is an alternating current in 8, while on the contrary, the tube 24 will light up on the passage of an alternating current in 8 and will be extinguished on the absence of this alternating current.

40 For seeking the direction of an emitter both frames 1 and 2 receive for instance the current of said emitting station. The currents received by said frames are in opposition, and if the frame 1 for instance is in the direction of the emitting station, the induction will reach a maximum at 8, since no current flows through the frame 2. On the contrary, if frame 2 is in the direction of the emitting station the induction will also reach a maximum at 8, since frame 1 offers no 45 opposition, supposing, of course, that the frames 1 and 2 are mounted on a common vertical axis and always form an angle of 90° between each other.

If one of the frames forms an angle of 45° with the emitting station the induction will be the same in frames 1 and 2. Since no high frequency current is then present at 8, the neon tube 19 is lighted and this is an indication that the bisecting line of the angle between both frames is in the direction of the emitting station. 55

It may thus be seen that during a complete revolution of the frames 1 and 2 there will be produced four flashes of the tube 19 on passing 60 each of the bisectors of the planes of the frames in the direction of the emitting station. On the other hand, there will be produced a flash of the tube 24 on each passage of the plane of each frame in the direction of the emitting station.

70 For providing a suitable mobility of the frames in establishing the desired arrangement of the circuits, the frames 1—2 will be mounted on a common axis 26 which is vertically supported, as diagrammatically shown in Fig. 2, in order that 75 they may rotate in suitable bearings which are

not shown in the drawings. Through a pulley 27 suitably connected with any source of power which is not shown in the drawings the frame unit may receive a rotary movement with a suitable velocity, and an index-hand 28 fast on axis 26 travels across a fixed scale 29. Suitably arranged and insulated conductor rings 30 are mounted in any desired number on the axis 26. Said rings, which are suitably connected with the frames 1 and 2, are provided with brushes 10 of any suitable construction which are connected to an amplifying device diagrammatically shown at 31, and which may be provided with the arrangement shown in Fig. 1 for controlling the illumination of the neon tubes 19 and 24. 15

When the frame unit 1—2 is rotated, the tube 19 for instance flashes on each passage of one of the bisecting lines 32—33—34 or 35 in the direction of the emitting station. If the speed of rotation of the frames is for instance 600 20 R. P. M. there will be 2400 flashes of the tube 19 by means of which the index 28 is illuminated. Since said flashes are always caused by the passage of each of the bisecting lines in the direction of the index 28, said index 28 will be 25 successively illuminated on each passage of one of the bisecting lines 32—35 in the direction of the emitting station, so that by stroboscopic effect the eye will see the index 28 as continuously 30 illuminated in four directions, one of which will be the direction of the emitting station.

The tube 24 flashes when a frame passes in the direction of the emitting station, so that the flashing period of the same is longer, since the moment in which the intensity of the current in both frames is the same has a very short duration. Said tube 24 is of no particular use in the case of Fig. 2 with ordinary frames, which on the contrary, it may be made of great use by substituting for said ordinary frames other frames 40 having a directive effect as shown by way of example in Fig. 6. In this case the amplifier receives a current which grows more and more intense as the rotation of the frame progresses, and reaches a maximum which is attained when the direction of one side of the frame is in line with the emitting station. Then by using the maximum receiving current for illuminating the tube 24, a momentary illumination of said tube is obtained for every revolution when the frame 50 is approximately in the direction of the emitting station.

Thus, if the device shown in Fig. 2 comprises two frames with a directional effect, there will be two reception curves which will give two points 55 of the same value when two bisecting lines only pass in the direction of the emitting station, as will be more particularly explained hereinafter. There will be also two points with a maximum current and said maximum points will correspond, by adjusting the plate tension to cause the illumination of lamp 24 in two positions of the index 28.

Both positions will be the positions in which the frames with a directive effect are in line with the emitting station, (as the index is in the bisecting line of the planes of the frames). As there are two bisecting lines forming an angle of 180° with each other, the neon tube 24 indicates the bisecting line which lies in the direction of the emitting station, since said tube 24 will flash on each of said bisecting lines in an angle of approximately 45° on each side as will be explained hereinafter. 70

Naturally, various solutions may be considered 75

for the realization of the rotating index; for example, that which consists in illuminating simply by two luminous sources an index fitted at the axis; this index being any kind, constituted by a needle, a circle, sector or otherwise, provided that it has a datum mark indicating a direction with respect to the axis. In the same way, the luminous sources may be of any form, and may, for example, be fixed on the index as in Fig. 3. A fixed dial 36, for example of glass, has two scales 37, 38 over the whole of the circumference, and in a lower plane the index 28 is fitted on the spindle 26 which is rotatable in a plane parallel to that of the dial 36. The index 28 comprises two neon tubes 39, 40 connected electrically by a collector 41 to the amplifier 31. A counter weight 42 counter-balances the index in order to maintain rotation, without vibration, in all planes. Above the neon tubes, two slots 43 and 44 in the index permit an observer placed above the dial to see on such dial two luminous beams such as 45, 46, coming from the neon tubes 28 and 29 when they are illuminated, and occupying a different position on the scales 37, 38, according to the position of the index. The axis of rotation of the index 28, while being vertical, horizontal or in any other position, cannot be confused with that of the rotating frames, and it is therefore sufficient to synchronize the movements of rotation by a mechanical or electrical connection.

Any kind of directional frame aerial may be used provided that the reception, according to the orientation, gives a maximum in one direction. One type of frame aerial, already known, and described as an example, is shown in Fig. 4, where 45 is the frame proper, 46 a variable resistance grounding the center of the frame, and 47 is an amplifying valve, the grid 48 of which is connected at 49 to the frame. The tuning system 50 is composed of two equal condensers grounded through a fixed condenser 51 to the ground 52, and is connected by lead 53 to the filament of the valve 48. There is thus an asymmetrical reception curve which avoids the 180° uncertainty. Any other device giving an asymmetrical curve may be used, and which furthermore, may be capable of comprising several maxima or minima.

To obtain a good reception of the signals two perpendicular frames of large dimensions are preferably used. As it is not easy to rotate such frames, two large and fixed wave collecting frames are preferably used, said frames being perpendicularly arranged with any desired orientation and comprising each a small frame, the winding of which is connected in series with the winding of the large frame, the tuning of each of said frames being obtained by means of a variable condenser. Both of said large frames may be compensated and of like dimensions, their middle point being grounded.

Such a device is shown diagrammatically in Fig. 5, in which the windings 53, 54 are of the same value as the large perpendicular frames. 55 and 56 are two coils of the same value, each of which is also perpendicularly arranged and wound in the same direction as the winding of the corresponding large frame, and each being arranged in the same corresponding plane.

With the tuning system 57 it is possible to obtain the resonance of both circuits with the frequency of the emitter the direction of which it is desired to know.

The field created by the emitting station and

received by each of the large frames 53 and 54, the intensity of which is received by each of said frames, depends upon the orientation of the system, will be reproduced in the small frames, which are directed exactly in the same way.

Through this contrivance it is possible to obtain a large wave collector and to reproduce the field received by said large frames in a more reduced space. If a coil or a third frame is placed inwardly of the small frames, which latter reproduce the field received by the large frames, said coil or third frame may be used as if the field in which it rotates were the real but amplified field. It is then possible to reproduce the apparatus according to Fig. 1 or Fig. 2 by rotating both the frames 55 and 56 at 600 R. P. M. for instance (this being easy to obtain if they have only small dimensions) in the field created by the windings.

Both large frames 53, 54 (Fig. 5) induce currents in the windings 55, 56 of smaller dimensions, which currents are exactly proportional to the currents received in 53 and 54 and thus the large frames reproduce the field which they receive.

In the inner part of both said small frames 55 and 56 are two perpendicular impedances 58, 59 fast on an axis which may be rotated.

The said impedances 58 and 59 form two strictly identical perpendicular windings, and when both impedances are so orientated that one of them is in the direction of the emitting station, this coil will be traversed by a maximum current, while the other will not be traversed by any current, and vice versa.

When the bisecting line of both coils is in the direction of the emitting station and if said device with two coils is simply formed of two like windings, the intensity of the current will be the same in both, exactly as in the case of the frames 1 and 2 according to Fig. 2 but on a reduced scale.

With an amplifier and neon tubes as described before an indication of the direction will be obtained.

Both said perpendicular coils may also be considered as the two halves of the winding of one and the same frame, the two outlet terminals of which are the extremities, and are connected to the amplifier.

In this way, the differential device is realized in the frames themselves, and there is no current at the amplifier when the two windings or halves of the frame receive the same current. Naturally, this construction does not in any way alter the principle of the invention, and it would function properly if directly in the space a single frame were used composed of two orthogonal windings of direct differential action.

There may also be provided (Fig. 5) two small directive effect frames or again a single small frame with two windings and with directive effect. Each of the windings being one half of the frame, the center point 60 may be grounded at 61 through a resistance 62, and may be tuned by two coupled condensers 63, the center point of which is also grounded through the fixed condenser 63'. The frame at 64 and 65 is connected to the amplifier 66. Naturally, any other means for obviating indetermination or for giving the directive effect, may be used, as for example that means which consists in adding an aerial to the frames.

Referring to the arrangement shown in Fig. 6, the wave collector is constituted by two frames 1 and 2, electrically independent but equal, and placed in perpendicular planes such that the axis 67 of intersection of these planes is vertical.

The center point of the winding of each of these frames is grounded at 68, and tuning is effected by two condensers 69 and 70 of the same value and having a single control.

In series with each of the windings of the large frames which, without inconvenience, may have several meters of surface, two other small frames or coils 71 and 72 repeat in a restricted volume the field received by 1 and 2.

The two small frames or coils 71 and 72, of small height, are exactly identical with each other and each is in the same plane as the winding 1 or 2 with which it is in series.

Naturally, the field reproduced by frames 71 and 72 will have the same direction as that received by windings 1 and 2, if, of course, the conditions of symmetry in the windings are followed and also if the respective dimensions of each of the members are strictly equal.

Inside the frames 71 and 72 there is an impedance in the form of a frame or coil 73 constituted by two perpendicular windings fixed on a spindle 74 having the same geometrical axis 67 as the frames 1 and 2, although the frames 1 and 2 are fixed; the coil 73 of two perpendicular impedances constitutes a search coil and can rotate with the axis 74 which comprises at its lower part an index 75 indicating the direction of a bisector of the impedance 73, this index 75 rotates with respect to a fixed dial 76 illuminated stroboscopically during its rotation by glow discharge tubes 77 and 78 dependent on the amplifier. The center point 79 of the winding of the frame 73 is grounded at 80 through an adjustable resistance 81.

The tuning of the frame 73 is accomplished by a double condenser 82, the center point of which is grounded at 80 through the capacity 83. One of the extremities of the windings of the frame 73 is connected to the grid 84 of an amplifying valve 85.

The rotating frame 73, composed of two perpendicular windings, may be considered as the wave collector of the amplifier, for it rotates in an artificial field which has the same orientation as the actual field. Furthermore, this frame is double, composed of two perpendicular windings in series, and it may be considered as giving the differential action of two identical frames of which the windings were perpendicular. There is thus on the grid 84 the resulting action of the two perpendicular windings of 73.

The system 73, 74, 75 rotates with a speed of, for instance, 600 R. P. M. and the neon tubes 77 and 78 may be fast with the index 75 as previously described.

The valve 85 is a high frequency amplifying stage, the same as the valve 86. Of course it is possible to add between valves 85 and 86 a certain number of additional stages if it should be necessary. The tuning of the resonant circuits is obtained by means of identical variable condensers which are coupled and controlled together by means of a single device 87 for instance.

A valve 88 operates as an oscillator, and its oscillating circuit 89 is tuned to a wave length such that the superposing of the primary wave amplified by 85 and 86 and with the secondary wave produced in 88, gives rise to a third alternating current of frequency sufficiently low to be amplified without too great losses or damping or distortion between stages. Naturally, this method of amplification described is given only as an example, and any other arrangement may be used; for example, that consisting in amplifying

only the initial current at high frequency; or in detecting it and amplifying it after modulation at low frequency or the like.

Having thus two waves of different frequencies, that of the amplifier 86 is directed by the fixed condenser 90 to the external grid of the valve 91.

The second wave is directed, in suitable volume by the condenser 92, to the second grid of the modulating valve 91.

The anode of the valve 91 is mounted in series with a resonant circuit 93 in which the tuning is obtained on a low wave length and on a frequency obtained by heterodyning and beating of the primary and secondary waves. The condenser 94 transmits this current of intermediary frequency to the amplifying valve 95; a certain number of amplifying stages for this intermediate frequency may also be provided, if desired. The valves 96 and 97 amplify said current still further and in series with the anode of 97 is mounted a final resonant circuit 98.

At least alternating current on the entry grid 84 of this very sensitive amplifier, there will be an appreciable current, and it is sufficiently amplified to be utilizable, in the resonant circuit 98 of the valve 97.

When the high frequency potential of the two windings of the rotating frame 73 cancel each other, there is no alternating potential on the grid 84, but at any other moment there is a difference between the currents produced in the windings of the frame 73 and there is an alternating potential on the grid 84.

In the resonant circuit 98 of the valve 97, there is exactly the same phenomenon; that is to say, when there is no alternating potential on the grid 84 there is no alternating current in the impedance of the circuit 98; but when there is the least high frequency potential on the grid 84, there is a strongly amplified current in the impedance of the circuit 98. It is shown below that the alternating current is only zero during a very short moment, twice for each rotation of the impedances 73, and that, on the other hand, for the remainder of the time there is an alternating current passing. Furthermore, through two maxima of amplitude, these maxima are produced a little before and a little after one of the positions of zero current and always on each side of the same zero, that is to say, in pairs, or again, at every 360° of the rotation of winding 73.

The impedance of the tuned circuit 98 is divided into two parts, one of which is coupled with another impedance 99 forming part of the grid circuit of a final valve 100.

The impedance 99 delivers to a resistance and acts on the grid of 100 in series with a rectifying device 101 which works as above described for the amplifier of Fig. 1. Any alternating current in the coil 99 corresponds to a lowering of the mean potential of the grid of valve 100 or, what is exactly the same, any alternating current, even of very low amplitude, acting on the grid 84 of the input valve 85, corresponds to a lowering of the mean potential of the grid of valve 100 and to the extinguishment of the neon tube 77 in series with the anode of valve 100.

A choke coil 102 may be useful and the neon tube 77 will be conveniently shunted by a capacity resistance 103.

The second part of the impedance of the network 98 is coupled with an impedance 104 which acts on the grid of a valve 105 acting as a detector, and also comprising an impedance 106 and a neon 75

tube 108 shunted by a capacity resistance and 107 in series with the anode of the valve 105.

It is easy to adjust the value of the plate current of the valve 105 in order to light the neon tube 78 as soon as a certain minimum amplitude of the alternating current at 104 is reached, the tube 108 remaining dark below said amplitude. The valve 105 works exactly in the same manner as the valve 22 in Fig. 1 which detects every alternating current acting on the grid. Through their repeated lighting and extinguishing the tubes 77 and 78 indicate the direction of the emitting station on which the amplifier is accorded. Tube 77 is lighted when no current passes, i. e. when it is traversed by both bisecting lines, one of which is in the direction of the emitting station, and the other the same direction but turned nearly 180°.

The tube 78 is lighted at points close to and on both sides of the bisecting line which really indicates the direction of the emitting station, thus permitting the determination of said direction. A close examination of the hereinafter described reception curves enables one to understand the mode of operation of the rotary parts of the amplifier in the described embodiment of the principle of the invention.

Both perpendicular windings of the small rotary frame of the device described above and shown in Fig. 6 are simple, tuned impedances forming two separate circuits which are independent from each other and could be considered as two perpendicular frames tuned to the same wave length. The reception curves of each of said frames, one of which is orientated in the axis 109 (Fig. 7) and the other in the axis 110, are circles 111—112 for one and 113—114 for the other, respectively.

Each of said two small perpendicular frames forming the rotary unit receives currents as the frames rotate and, said currents may be represented by two curves 115—116—117 and 118—119—120 (Fig. 8), spaced 90° apart and having the same shape, and possessing as in 121 and 122 (Fig. 8) points of the same value corresponding to angles of the same value between the emitting station and each of the frames, viz. angles of 45°.

According to the rotation of the unit, formed of both frames, about the vertical axis, when one of the two bisecting lines of the angles formed by both perpendicular planes of the frames passes in the direction of the emitting station, the current will have the same value in each of the two frames; said points *a*, *b*, *c*, *d* (Fig. 7) are repeated on each revolution of the frame unit.

By superposing both curves 115, 116, 117 (Fig. 8) and 118, 119, 120 of the current received by each of the frames, the current in each frame being supposed flowing in a contrary direction, a curve results which will represent the difference between the other two curves, and will have the shape 123, 124, 125, 126, 127, 128 in which the maximum points 129, 130 correspond to the moments when the frames pass in the direction of the emitting station. The minimum points, of no current, 126, 127, 128 correspond to the moments when the bisecting lines pass in the direction of the emitting station. Supposing that said curves result from the differential action of both frames on a third coil connected with the amplifier, the curve 129, 130, 126, 127 is the curve of the current on the terminals of the final tuned circuit. By regulating the plate potential of the detector for the illumination of the tube which it controls for an amplitude of

value denoted by numeral 160 (Fig. 8) there will be for each revolution of the two frames, four illuminations of this tube, that is, one at each maximum of amplitude of the current received at the entry to the amplifier, which current arises from the differential action of each of the frames.

The tube which lights up at zero current and which should indicate the direction of the emitter, would therefore light up at the points 126, 127, 128 of Fig. 8, that is to say, four times per revolution of the index or of the frames, and would only give relative indication with regard to the direction of the emitter.

If these two frames are replaced by the device shown in Fig. 6, that is to say, by two perpendicular windings of a frame of directive effect, or two perpendicular directive effect frames according to the position of these windings, there are two asymmetrical reception curves which each represent a maximum of reception.

These two reception curves may be represented (Fig. 8) the one by 132, 133, 134, 135 and the other by 136, 137, 138, 139, and it will be seen that they are displaced by 90°.

These two curves are superposed in the differential action of the two frames and the resultant of the difference of the two gives the curve 140, 141, 142, 143, 144, 145, 146, which represents at each revolution of the apparatus two maxima near each other on each side of the minimum point 148.

This resulting curve therefore presents two points 147, 148, of zero current, which correspond to the points of same value 146 and 150 of the two reception curves (Fig. 8) or the points *e* and *f* of the curves *g* and *h* of Fig. 7. These two points where the two frames in their rotation pass through a similar amplitude value correspond to the passage of a bisector in the direction of the emitter.

In Fig. 8 the time of illumination of the tube corresponding to the passage of the zero current is represented by T—1, while the time of illumination of the tube corresponding to the current maxima is represented by T—2.

At the points 147 the tube T—1 will light up during a very short interval of time at 152. At 153 tube T—2 will light up during the passage of the amplitude of value 160 of the resulting curve 141, 142. Then tube T—1 will light up afresh for the zero 148 in 153, the tube T—2 at 159 for the second maximum. Tube T—1 having made a revolution, will light up at the point 149 etc. There will thus be four illuminations per revolution, two per tube, the illuminations of T—1 being at 180° from each other, and the illuminations of tube T—2 on each side of the zero point 148. This dissymmetry permits the bearing of the emitter to be seen without any ambiguity.

The sources of light may be the tubes 77 and 78 of Fig. 6 and they may be arranged under the index 15 in Fig. 6 in the manner shown in Fig. 3. The graduated dial 36 in Fig. 3 may then be shown as viewed from above at 38 in Fig. 9, and on said dial the circumferential graduations corresponding to positions T—1 and T—2 will permit the reading of the angles and indications given by the flashes of said tubes 77 and 78.

At 154 and 155 in Fig. 9 are shown the short flashes of tube T—1 (or 77 in Fig. 6) at the time of the passage of the frames passing through the same reception value, i. e. through points 147 and 148 in Fig. 8 where the current is zero.

One of said zero points 148 is the point corre-

sponding to the direction of the emitting station, and said point is surrounded by two points of maximum amplitude of the resultant of the overlying curves. Thus it is possible to know that 5 131 in Fig. 9 is the direction of the emitting station, the flashes 156 and 157 being on both sides of said indication of the direction 131.

The index carrying both neon tubes rotates with both perpendicular windings secured fast on 10 the rotation axis 61 in Fig. 6. The rotation speed may be for instance 600 R. P. M. so that each of the neon tubes T-1 and T-2 will flash twenty times to the second under the dial 36 in Fig. 9, the rotation speed being ten revolutions to the 15 second and the flashes of each tube being produced twice for each revolution, so that there will be, under said conditions, ten flashes at point 154 in the direction 169 (Fig. 9), ten flashes at 155 in the direction of the emitting station 131, and ten at points 157 and 156, on 20 both sides of the direction 131.

Said frequency of the flashes is sufficient in order that all the flashes, in spite of being very short and instantaneous, seem to the eye to form 25 only a constantly luminous line which continually gives the direction of the emitting station 131 (Fig. 9).

If the device 73 (Fig. 6) did not receive a continuous rotation movement and if it were oriented 30 by hand, the four flashing positions of the tubes would appear only successively according to the orientation of the device 73. Of course, in these conditions, the principle of the invention remains the same. However, the stroboscopic effect is 35 preferably produced through a continuous rotation of the axis with a sufficient speed.

If the system used for removing the uncertainty were different according to the reception 40 curve of the frames for the determined orientations, there might result owing to the differential action, a third curve having a certain number of maxima or minima of current, but as long as there is dissymmetry in the illuminations either 45 by the rotating position of the illuminations of the different tubes, or by the relative position of the illuminations of the different tubes, it will be possible to determine the direction of the emitter and the principle of the invention remains applicable.

50 In one of the applications of said principle, shown in Fig. 6, the device with the large frames 1-2 and the small frames 71 and 72, by which the field created by the emitter on which the accord has been made, is exactly repeated, and thus 55 reconstituted, permits obtaining a great amplification both of the distance and the power of the emitter, on which depends the precision of the determination.

The sensitivity of the device may become very 60 great and grows with the amplification. In fact, the overlying reception curves always give two zero points for the high frequency alternating current in the amplifier at the inlet on the grid of the first valve as well as in the circuit which is accorded in series with the anode of the valve, 65 97. However, on the least difference in the amplitude of the current received in one of the frames at 73 there will be a weak alternating current on the input grid; said current is 70 considerably amplified and the curve of said current as a function of the angular position of the frames is similar to the curve shown at 161, 162, 148, 164, 165, 149, 166. In said curve the zero points are still present, but the maxima are much greater 75 and the already very short time during which

points 148 and 149 correspond to short and exact flashes of the tube T-1 indicating the direction of the emitter, is more exactly delimited and corresponds to a smaller angle 170 (Fig. 9) on the graduated dial.

Said precision is limited only by questions of inertia (which may be practically reduced to 1/100,000, of a second) of the lighting of the neon tubes on the one hand and the frequency of the currents acting on the tube; in a convenient form of execution it is possible to attain a quarter of a degree for the angle 170 (Fig. 9).

The flashing of the tube T-2 which eliminates the uncertainty need not be as short as for the other tube and in fact it lasts for a certain time 15 which may be controlled and adjusted by the value of the plate current of the detector valve 105 controlling the tube of the coupling of the coils 104 (Fig. 6).

If the tuning of the amplifier can not be made 20 on a single emitter only, and if a second emission were received at the same time, two sharply distinct indications would then be given on the graduated dial and the direction of both emitting stations could be determined. From the latter 25 observation it may be seen that a disturbing station would not destroy or prevent the indication given by the device but that, on the contrary, the direction of both the station sought and of the disturbing station would be determined by 30 the instantaneous nature of the indications.

The action of parasitical currents has no effect 35 on the indication of the direction, for they produce only flashes which have no synchronism with the rotation of the index.

The immediate determination of the position 40 of any emission may take place by a simple tuning of the amplifier on said emission. It is then very easy, by triangulation and by determination 45 of the position of different emitters, to determine the position of a receiving device, for instance in the aeronautics. Every aircraft provided with such a radio-goniometric receiver is in a position to always exactly determine where it is and the direction it must take, without having to take 50 measurements other than the data indicated by the apparatus. Said device may also be used in the navigation and in all the cases where it is necessary to know the direction of an emitter.

What I claim is:—

1. Radio direction finding apparatus, comprising 55 two receiving frame aerials disposed at an angle to each other, means for tuning said aerials, substantially identical impedances, wound inversely with respect to each other, with which the tuning means for the respective aerials are connected, a tuned impedance inductively coupled in common to said first-mentioned impedances, a plurality of lamps, circuits for said lamps operatively associated with said common impedance, and means in each of said circuits for controlling the current flow through the lamps, whereby one of the lamps is energized only when no current passes through said common impedance, whereas the other lamp is energized when 60 the current flow through the common impedance exceeds a predetermined value.

2. Radio direction finding apparatus, comprising 65 two rotatable receiving frame aerials disposed at an angle to each other, means for tuning said aerials, and comprising substantially identical impedances wound inversely with respect to each other, a shaft carrying said aerials, a balanced radial index disposed on said shaft aerials and rotatable therewith, slots on said index, along an 70 75

axis transverse to the axis of rotation, lamps disposed in said slots, a transparent dial through which the index is visible, and on which is received the indications from the lamps, a tuned

on each side of that flash of the first-mentioned lamp which occurs when the current flow is equal in the two aerials, and which indicates the direction of the emitter.

5

5 common impedance with which said first-mentioned impedances are operably associated, amplifying means connected with said common impedance, circuits for said lamps connected across said amplifying means, and means in each of said 10 circuits for controlling the current flow through the lamps, whereby one of the lamps is energized only when no current passes through said common impedance, whereas the other lamp is energized when the current flow through the 15 common impedance exceeds a predetermined value.

6. Radio direction indicating apparatus, comprising loop aerials disposed at an angle to each other, means for tuning said aerials on an emitter, means for effecting an apparent rotation of the field induced in said aerials, a circuit associated with said means, and containing means 10 for displacing the maxima of said aerials relative to each other, a plurality of lamps, circuits for said lamps operatively connected with said first circuit, means in each of said circuits for controlling the current flow through the lamps, 15 whereby one of the lamps is energized only when the current flowing through said aerials is equal, and the other only when the current through said aerials is asymmetrical and approaches a maximum in one of the aerials, a pointer rotatable at a speed proportional to the current flow through the lamps, causing two flashes of each lamp for each 20 rotation of the field of the aerials, the means in the first-mentioned circuit causing the flashes of that one of the lamps which corresponds to the maxima in the aerials to be closely adjacent to each other, and one closely on each side of 25 that flash of the other lamp which occurs when the pointer is directed towards the emitter, the rotational speed of the aerials, and the consequent continuity of emission, being such that the 30 flashes appear to the eye to be continuous, and the illuminated pointer appears to be continuously directed towards the emitter.

20

3. Radio direction finding apparatus, comprising two fixed receiving frame aerials of large dimensions disposed at an angle to each other, two smaller coils disposed at a corresponding angle to each other and to which said aerials are connected, a third coil disposed for rotation within said small coils, means for tuning said aerials, means for tuning and amplifying the output of said 25 third coil, a plurality of lamps, and means for differentially connecting said lamps with said third coil in such manner that one of the lamps is illuminated only when the current flowing through the coil is zero, and the other lamp 30 being illuminated only when the current flowing through the third coil reaches a predetermined value.

4. Radio direction indicating apparatus, comprising loop aerials disposed at an angle to each other, means for tuning said aerials on an emitter, means for effecting an apparent rotation of the field induced in said aerials, a circuit associated with said means, and containing means 35 for displacing the maxima of said aerials relative to each other, a plurality of lamps, circuits for said lamps operatively connected with said first circuit, means in each of said circuits for controlling the current flow through the lamps, whereby one of the lamps is energized only when the current flowing through said aerials is equal, and the other only when the current through said aerials is asymmetrical and approaches a maximum in one of the aerials, and a pointer rotatable at a speed proportional to the 40 rotational speed of the aerials, causing two flashes of each lamp for each rotation of the field of the aerials, the means in the first-mentioned circuit causing the flashes of that one of the lamps which corresponds to the maxima in the aerials to be closely adjacent to each other, and one closely on each side of 45 that flash of the other lamp which occurs when the pointer is directed towards the emitter, the rotational speed of the aerials, and the consequent continuity of emission, being such that the 50 flashes appear to the eye to be continuous, and the illuminated pointer appears to be continuously directed towards the emitter.

35

4. Radio direction indicating apparatus, comprising loop aerials disposed at an angle to each other, means for tuning said aerials on an emitter, means for effecting an apparent rotation of the field induced in said aerials, a circuit associated with said means, and containing means 45 for displacing the maxima of said aerials relative to each other, a plurality of lamps, circuits for said lamps operatively connected with said first circuit, means in each of said circuits for controlling the current flow through the lamps, whereby one of the lamps is energized only when the current flowing through said aerials is equal, and the other only when the current through said aerials is asymmetrical and approaches a maximum in one of the aerials, and a pointer rotatable at a speed proportional to the 50 rotational speed of the aerials, causing two flashes of each lamp for each rotation of the field of the aerials, the means in the first-mentioned circuit causing the flashes of that one of the lamps which corresponds to the maxima in the aerials to be closely adjacent to each other, and one closely on each side of 55 that flash of the other lamp which occurs when the pointer is directed towards the emitter, the rotational speed of the aerials, and the consequent continuity of emission, being such that the 60 flashes appear to the eye to be continuous, and the illuminated pointer appears to be continuously directed towards the emitter.

40

5. Radio direction indicating apparatus, comprising loop aerials disposed at an angle to each other, means for tuning said aerials on an emitter, means for effecting an apparent rotation of the field induced in said aerials, a circuit associated with said means and containing means for displacing the maxima of said aerials relative to each other, a plurality of lamps, means for rotating said lamps at a speed proportional to that of the rotating field, a transparent scale disposed above said lamps, circuits for said lamps operatively connected with said first-mentioned circuit, and means in each of said lamp circuits for controlling the current flow through the lamps, whereby one of the lamps is energized only when the current flowing through said aerials is equal, and the other only when the current flowing through said aerials is asymmetrical and approaches a maximum in one of the aerials, the said first-mentioned circuit being capable of displacing the maxima of said aerials relative to each other in such manner that the flashes of that one of the lamps corresponding thereto occur 65 closely adjacent to each other on the scale, one

7. Radio direction indicating apparatus, comprising loop aerials disposed at an angle to each other, means for tuning said aerials on an emitter, means for effecting an apparent rotation, at high speed, of the field induced in said aerials, a circuit associated with said means and containing means for displacing the maxima of said aerials relative to each other, a plurality of lamps, means for rotating said lamps in synchronism with said rotating field, a transparent scale disposed above said lamps, circuits for said lamps operatively connected with said first-mentioned circuit, means in each of said lamp circuits for controlling the current flow through the lamps, whereby one of the lamps is energized only when the current flowing through said aerials is equal, and the other only when the current flowing through said aerials is asymmetrical and approaches a maximum in one of the aerials, the means in the lamp circuits, as an incident to current flow through the aerials, causing two flashes of each lamp for each rotation of the field of the aerials, the means in the first-mentioned circuit causing the flashes of that one of the lamps which corresponds to the maxima in the aerials to be closely adjacent to each other, and one closely on each side of 70 that flash of the other lamp which occurs when the pointer is directed towards the emitter, the rotational speed of the aerial field causing the illumination to have stroboscopic effect, so that the flashes of the one lamp, indicating the direction of the emitter, and the adjacent flashes on each side thereof of the other lamp, give the effect of continuous illumination.

55

8. Radio direction indicating apparatus, comprising a directional antenna, the coils of which are disposed at an angle to each other, the directional antenna causing the maxima of said coils

60

65

70

75

to be displaced relative to, but closely adjacent each other, means for turning said coils on an emitter, means for effecting an apparent rotation at desired speed of the field induced in said coils, 5 a plurality of lamps, circuits for said lamps operatively coupled with said coils, means in each of said circuits for controlling the current flow through the lamps, whereby one of the lamps is energized only when the current flowing through 10 said aerials is equal, and the other only when the current through said aerials is asymmetrical and approaches a maximum in one of the aerials, and a pointer rotatable at a speed proportional to the rotating field and illuminated by the lamps, to 15 indicate the direction of the emitter, the displacement of the maxima being such that the flashes of the lamp corresponding thereto occur closely adjacent to each other during a revolution of the rotating field, one on each side of that flash 20 of the other lamp which occurs when the pointer is directed towards the emitter.

9. Radio direction indicating apparatus, comprising a directional antenna consisting of fixed loop aerials disposed at an angle to each other, 25 means for tuning said loop aerials to an emitter, auxiliary loop aerials, connected one to each of said first mentioned loop aerials and disposed with the same angular relation relative to each other; a coil consisting of two portions which have 30 the same angular relation to each other as do the aerials, rotatably disposed within and along the axis of said auxiliary aerials, a shaft for said coil means for connecting the mid-portion of said coil to the ground, means for tuning said coil, the 35 directional antenna causing the maxima of said aerials to be displaced relative to but closely adjacent each other, a plurality of lamps, circuits for said lamps operatively coupled to said auxiliary aerials through said coil, means in each 40 of said circuits for controlling the current flow through the lamps, whereby one of the lamps is energized only when the current flowing through said aerials is equal, and the other only when the current through said aerials is asymmetrical and 45 approaches a maximum in one of the aerials, a

pointer fixed to the shaft of said coil, and a scale traversed by said pointer, the said pointer being illuminated by said lamps, that one of the lamps which corresponds to the maxima flashing twice during each rotation of the coil, in closely adjacent positions, one on each side of that flash of the other lamp which occurs when the pointer is directed towards the emitter, the rotational speed of the coil being such that the lamps produce a stroboscopic effect. 10

10. Radio direction indicating apparatus, comprising loop aerials disposed at an angle to each other, means for tuning said aerials on an emitter, means for effecting an apparent rotation of the field induced in said aerials, a plurality of lamps, 15 circuits for said lamps, each of which circuits contains an audion, the circuit for one of said lamps containing a unidirectional means controlling the bias on the grid of the audion thereof, an amplifying circuit coupled to both said lamp circuits and connecting with said aerials, the current rectified in one of said lamp circuits by said unidirectional means applying a negative bias to the grid of the corresponding audion at those times when current flows through the 20 aerials into the amplifying circuit, thus preventing energization of the corresponding lamp, and permitting the illumination of the latter only when the current flowing through said aerials is equal, the grid of the audion in the circuit of the 25 other lamp, on the other hand, being directly coupled with the corresponding amplifying circuit, so that it is illuminated only when the current through said aerials approaches a maximum, a circuit for displacing the maxima of said aerials 30 relative to each other, and a pointer rotatable at a speed proportional to the rotating field and illuminated by said lamps, the lamp corresponding to the maxima flashing twice for each revolution of the rotating field at points closely adjacent each other, one on each side of that flash of the other lamp which occurs when the pointer is directed towards the emitter. 35 40

RENÉ JEAN HARDY. 45
